UNITED STATES PATENT OFFICE.

GEORGE JURESIKIN, OF WILKES-BARRE, PENNSYLVANIA.

MINE-DRILL.

1,374,744.

Specification of Letters Patent. Patented Apr. 12, 1921.

Application filed September 19, 1919. Serial No. 324,794.

To all whom it may concern:

Be it known that I, GEORGE JURESIKIN, a citizen of Czechoslovakia, residing at Wilkes-Barre, in the county of Luzerne and State of Pennsylvania, have invented certain new and useful Improvements in Mine-Drills, of which the following is a specification.

The primary object of the present invention resides in the provision of a mine drill wherein the drill with its driving shaft is vertically adjustable for drilling in a bank at different heights with the support for the forward end of the drill shank being vertically adjustable for engaging the ceiling and floor of a mine room.

A further object of the invention is to provide a mine drill wherein the driving mechanism for the drill is supported at a point considerably spaced therefrom with vertically adjusting means for the rear end of the support spaced from the driving mechanism.

With the above and other objects in view, the invention consists in the novel form, combination and arrangement of parts herein fully described, shown in the accompanying drawings, and wherein like reference characters indicate similar parts throughout the several views.

In the drawings,

Figure 1 is a side elevational view of a mining drill constructed in accordance with the present invention,

Fig. 2 is a top plan view thereof showing the driving mechanism for the drill,

Fig. 3 is a rear elevational view showing the rear supporting legs for the driving connection frame,

Fig. 4 is a rear elevational view of the forward drill supporting rack extending between the ceiling and floor of a mine,

Fig. 5 is an enlarged detail view, partially in section of the upper end of the forward drill supporting frame,

Fig. 6 is a vertical sectional view of the upper end of the drill supporting rack with the bearing block for the drill shank shown in end elevation,

Fig. 7 is a cross sectional view taken on line VII—VII of Fig. 5,

Fig. 8 is a cross sectional view taken on line VIII—VIII of Fig. 5 showing the drill shank supporting block removably supported in the rack teeth on the frame,

Fig. 9 is a fragmentary detail sectional view of the pin locking connection between the sections of the rear supporting legs, and

Fig. 10 is a detail sectional view of the rear legs showing the dove-tailed connection between the leg sections.

Referring more in detail to the accompanying drawings, the present invention of mine drill is shown as operatively positioned in the room of a mine of which room there is illustrated the ceiling 1, the floor 2 and the wall 3 being operated upon, there being shown in Fig. 1 pockets 4 and 5 that have been cut by the drill to be described.

The supporting legs for the frame carrying the driving mechanism will first be described and are shown more clearly in Figs. 1, 2, 3, 9 and 10, the supporting legs being arranged in upwardly converging pairs as shown in Fig. 3 and comprising upper sections 6 and lower sections 7, the upper sections being connected by transverse links 8 to limit the spreading movement of the legs. As shown in Fig. 1, the lower section 7 carries a dove-tailed shaped rib 9 upon its inner face adapted for sliding reception in the dove-tailed groove 10 formed in the adjacent face of the upper section 6, while the adjusted positions between the leg sections are maintained by pins 11 passing through registering openings 6' and 7' in the leg sections respectively.

The upper ends of the leg sections 6 are pivotally secured as at 12 to the rear end of the rectangular frame 13 shown more clearly in Figs. 1 and 2, the frame 13 supporting the driving mechanism for the drill. A central cross shaft 14 is journaled transversely of the frame 13 and carries a relatively large gear 15 within the sides of the frame 13 while transverse shafts 16 and 17 are journaled in the frame at opposite sides of the shaft 14, the shaft 16 carrying a pinion 18 in mesh with the gear 15 while the shaft 17 has fixed thereto a pinion 19 in mesh with the gear 15, motion being imparted to the meshing gears by the crank handle 20 secured to the outer projecting end of the shaft 16. A driving shaft 21 is journaled at its rear end in the bearing 22 in the forward end of the frame 13 and has connected to the inner end thereof a bevelled pinion 23 in constant mesh with the bevelled pinion 19' formed integral with the pinion 19, the forward end of the driving shaft 21 having connected thereto a drill 24.

A vertically adjustable rack for supporting the forward end of the drill shaft 21 is provided and as shown more clearly in Figs.

1 and 4 to 8, the same including, as illustrated in Fig. 4, an upper section embodying a cross head 25, having depending side bars 26 slidable over the upstanding slide bars 27 of the lower cross member 28, the lower cross member 28 carrying a floor spur foot 29 for engagement with the floor 2 of the mine, while the upper cross head 25 has a central threaded opening therein through which the screw 30 having a pointed upper end 31 is adapted for entering the roof 1 of the mine for anchoring the rack, the screw being operated by the handle 32 at its lower end. As illustrated in Fig. 5, the supporting rack is vertically adjustable, which adjustment comprises in detail metal bands 33 inclosing the side bars 26 and 27 of the rack, which bars are secured at 34 to the bars 26. The side bars 26 and 27 are provided with transverse openings 35 and are adapted to be brought into registration for the reception of pins 36 entering the registering slots to hold the rack bar in its adjusted position.

As illustrated in Figs. 6 and 8 corresponding side faces of the bars 26 and 27 are provided with corresponding vertically spaced sockets 37 into which are adapted to be received the opposite bearing ends 38 of a saddle 39, the saddle having a central bearing opening 40 and a shifting handle 41 positioned therebeneath.

As illustrated in Figs. 1 and 2, the drive shaft 21 is journaled in the bearing 40 of the saddle 39 with the drill 24 positioned in the pocket 5 of the mine wall 3. By oper-

ing the crank 20, driving motion for the shaft 21 and drill 24 is communicated thereto through the meshing gear and pinions illustrated in Fig. 2. It is thought that the vertical adjustment of the driving mechanism supporting frame 13 will be understood from the description of the adjustable leg connection shown in Figs. 3 and 9 while the height adjustment of the forward supporting rack is also apparent. By releasing the end bearings 38 from the bearing sockets 37 and changing the height thereof, the drill 24 may be caused to operate upon any part of the mine wall such as the pocket 4 in Fig. 1 by positioning the saddle at the desired elevation.

While there is herein shown and described what is believed to be the preferable embodiment of the invention, it is nevertheless to be understood that minor changes may be made in the form, combination and arrangement of parts without departing from the spirit and scope of the invention as claimed.

What is claimed as new is:—

A drill of the type described comprising a mechanism supporting frame, supporting legs for one end thereof, a drill shank extending from the other end of the frame, and an adjustable rack for supporting the forward end of the shank and spaced from the mechanism frame.

In testimony whereof I affix my signature.

GEORGE JURESISIN.
